(57) **CLAIM**

The ornamental design for a tire, as shown and described.

DESCRIPTION

FIG. 1 is a front view of the tire showing my new invention;

FIG. 2 is a partial front view thereof;

FIG. 3 is a right side view thereof;

FIG. 4 is a left side view thereof; and,

FIG. 5 is a perspective view thereof.

The broken lines depict the location and borders of the enlarged fragmentary view of FIG. 2 and form no part of the claim.

1 Claim, 5 Drawing Sheets

FIG. 1

FIG. 2

FIG. 3

FIG. 4

FIG. 5
